UNITED STATES PATENT OFFICE.

HENRY W. BOGART, OF CLEVELAND, OHIO, ASSIGNOR TO THE McMYLER INTERSTATE COMPANY, OF BEDFORD, OHIO, A CORPORATION OF OHIO.

ROTARY STEAM-ENGINE.

1,275,373.

Specification of Letters Patent. Patented Aug. 13, 1918.

Application filed October 29, 1914. Serial No. 869,185.

To all whom it may concern:

Be it known that I, HENRY W. BOGART, a citizen of the United States, residing at Cleveland, in the county of Cuyahoga and State of Ohio, have invented a certain new and useful Improvement in Rotary Steam-Engines, of which the following is a full, clear, and exact description.

The object of this invention is to produce an efficient rotary steam engine; and the invention consists in the construction and combination of parts shown in the drawing and hereinafter described, and briefly defined by the appended claims.

In the drawing, Figure 1 is a front elevation, for most parts in longitudinal vertical section, of an engine embodying the invention. Fig. 2 is a vertical transverse section through the engine cylinder when the parts therein are assembled in working relation. Fig. 3 is a vertical longitudinal section through the empty engine cylinder. Fig. 4 is a vertical transverse sectional view in the plane indicated by line 4—4 on Fig. 5. Fig. 5 is a vertical longitudinal section of the fly wheel and adjacent parts of the engine shaft. Fig. 6 is an elevation partly broken away of one of the packing rings 80. Fig. 7 is a sectional view of said packing ring. Fig. 8 is an enlarged transverse section in the plane of line 8—8 on Fig. 1; and Fig. 9 is a transverse section in the plane of line 9—9 on Fig. 1.

Referring to the parts by letters, 10 represents the cylinder which contains an elliptoid recess 11, the ends of which are closed by the two bolted arm heads 12 and 13. Within the recess 11 are four concentric cylindrical members arranged one within another, viz., the rotatable cut-off sleeve 20, the fixed non-rotatable steam inlet sleeve 30, the hollow rotatable engine shaft 40, and the rotor 50. The sleeve 30 passes out of the cylinder recess through a hole in the head 13, and has outside of said head a flange 31. This flange is bolted to the head 13 and to the flange 35 of the steam inlet pipe 36.

The engine shaft 40 is tubular from end to end. It is rotatably mounted in a suitable bearing 90 which is carried by a fixed pedestal 91. From this bearing the shaft extends in both directions. At one end it projects into the cylinder 10, passing through a hole in the head 12, and through

a stuffing box 14 carried by said head. The 55 part of the shaft within the recess is of enlarged external diameter and embraces and nicely fits the cylindrical inlet sleeve 30.

The cylindrical cut-off sleeve 20 is fitted to and is rotatable in the fixed inlet sleeve 60 30, and is open at the end which is adjacent to the inlet pipe 36. A shaft 25 has a driving connection with the opposite end of the cut-off sleeve and passes therefrom through an axial hole in shaft 40, and projects from 65 the left end of said shaft. The end of the cut-off sleeve 20 has a diametrical slot which receives fingers which project in diametrically opposite directions from the shaft 25, as shown in Fig. 8. The projecting left end 70 of the shaft 25 is connected with the engine shaft 40 by automatic governor mechanism to be presently described, whereby the engine shaft and the shaft 25 and the cut-off sleeve 20 connected therewith, must rotate 75 in substantial unison, although the engine shaft, on the one hand, and the cut-off sleeve and its shaft, on the other hand, are permitted a slight relative angular movement.

The rotor 50 embraces and is keyed to the 80 enlarged part of the engine shaft within the cylinder. This rotor is a cylinder whose diameter is substantially equal to the smallest diameter of the elliptoid recess 11 within the cylinder. Packing strips 15 are set into 85 the peripheral wall of the cylinder recess at diametrically opposite points where the recess is of smallest diameter, and these engage the cylindrical periphery of the rotor 90 from end to end.

The rotor is formed with two diametrically opposed radial slots 52, each of which extends from one end of the rotor to the other, and from the periphery of the rotor inward a suitable distance. In each of these radial 95 slots a radially movable piston blade 60 is slidably fitted. These blades are capable of sliding toward and from the axis of the rotor in said slots, and do so slide sufficiently to enable their outer edges to always engage 100 the inner peripheral wall of the elliptoid recess. When the rotor is being turned, the centrifugal force will be sufficient to cause these blades to remain in engagement with the elliptoid surface referred to, and even 105 when the rotor is not in motion these blades will generally remain in contact with said elliptoid surface. But in order to insure a

sufficiently close contact of the outer edges of the blades with said elliptoid surface, each of the heads 12 and 13 has formed in its inner face an elliptoid groove 16,—that is to say, a groove which corresponds in shape to the shape of the inner wall of the cylinder. Each of the blades 60, in that event, would have projecting from each of its ends a pin 61 which projects into and fits rather loosely the adjacent elliptoid groove. 10 Therefore when the rotor turns, these blades 60 will be positively moved inward and outward so as to substantially maintain the desired contact between their outer edges and the inner periphery of the cylinder. Adjacent to each of the radial slots 52, and behind the blade therein with respect to the direction in which the rotor turns, is the steam port 53 which extends from the center to the periphery of the rotor. Other ports 43, cut through the walls of the shaft 40, are in constant communication with these ports 53. Steam ports 33 are cut through the walls of the fixed steam inlet sleeve. 25 Each of these ports extends through an arcual distance of about 75 degrees.

There are diametrically opposed ports 23 formed through the walls of the cut-off sleeve 20, and when this cut-off sleeve is in its normal position relative to the engine shaft, these ports 23 are alined with the corresponding ports 43 in the shaft 40.

When steam is admitted to the engine from the inlet pipe 36, it goes into the cut-off sleeve. When this cut-off sleeve and the rotor and the engine shaft are turned to such positions that the ports 23 and 43 register and communicate with the ports 33, the steam admitted to the cut-off sleeve will 35 rush through these ports into the spaces between the periphery of the rotor and the cylinder. The steam pressure thereby exerted between the piston blades and the abutments, furnished by the overhanging 40 indrawing wall of the cylinder recess, will cause the rotor to turn, carrying with it the engine shaft, which, as before stated, is so connected with the cut-off sleeve that it also turns. Steam will be admitted to the steam 45 space within the cylinder around the rotor until the ports 23 in the cut-off sleeve pass out of communication with the ports 33 and become closed by the overhanging wall of the fixed sleeve 30.

50 Within the cylinder is a cored out exhaust passage 70 which discharges through an opening 71. This passage communicates with the space within the cylinder through two series ports 72 disposed, one series above 55 one of the packing strips 15, and the other series below the other packing strip 15. Each of the two exhaust ports 72 is preferably formed of a plurality of diagonally disposed slots, as shown in Fig. 2.

60 Normally, steam will be cut-off from the

cylinder when the rotor has turned through about 80 degrees of arc after the two blades 60 have passed the two packing strips 15. When these blades begin to pass the ports 72 the steam which had theretofore, by 70 pressure against the piston blades, caused the rotor to turn, will begin to exhaust.

The proper packing of the various joints so as to prevent wasteful escape of steam is 75 essential to the practical success of the described mechanism. The prevention of the escape of steam from the cylinder chamber at the ends of the rotor is taken care of by two packing rings 80 which are fixed to opposite ends of the rotor. These packing 80 rings project into circular grooves 17, and 18 in the cylinder heads 12 and 13 respectively. The outer circular walls of these grooves are engaged by the outer cylindrical surfaces of the packing rings. Obviously, 85 these engaging cylindrical surfaces must fit nicely together to prevent the escapement of the steam. In order to bring about this nice fit in a practical way, each of these packing rings is split, but the adjacent ends 90 of each ring are connected by a link 81.

This occupies a position in a groove 82 cut in the inner periphery of both ends of the ring. Normally the packing ring is made slightly larger in diameter than is required 95 to fit the groove. One of the pins 82 which connects a link with one end of the ring goes into a slightly elongated hole in either the ring or the link,—preferably the latter, as shown. The packing ring is slightly 100 contracted in diameter when it is inserted into the circular groove in the head. When in the groove, the ring expands slightly, and therefore fits tightly against the outer wall of the groove. After the engine has 105 been run awhile, however, the two engaging surfaces of the ring and the groove will wear upon one another until they come to exactly fit. The elongated slot 83 which receives the pin 82, by which the link and one end of the ring are connected, is made as near as possible to be of a length such that when this nice fit has been brought about, the pin will come in contact with the end of the slot, and thereby prevent any 110 further expansion of the ring. Thereafter these two nicely fitted surfaces will not wear to any great degree upon one another, and this nice fit so produced will persist for 115 a very long time. The connection between 120 the rotor and the packing ring is by means of screws 84, which pass through holes in the ring and screw into the rotor and have their heads in countersunk recesses in the ring, and springs 85 are placed in these recesses just inside of the heads, whereby the rings will be held by the springs in close contact with the rotor.

125 There will be some end thrust produced by the steam, tending to move the shaft 40 130

to the left in its bearing. In order to prevent such endwise movement, a thrust bearing is provided. The bearing sleeve 90, in which shaft 40 is mounted, is enlarged near 5 one end, and in this enlarged part of the sleeve, surrounding the shaft, a plurality of friction disks 92, 93, are placed. The disk 93 is pinned to the shaft, and likewise abuts against a shoulder 46 thereon, while the disk 10 92 at the other end of the series engages the end 94 of the bearing sleeve. The enlarged part of this bearing sleeve has its upper portion cut away so that these disks 92, 93, may be passed to the position shown, (see Fig. 15 9). In other respects the bearing sleeve and parts associated therewith are shown in familiar form. The rings 25^a will supply oil to the bearing surface between sleeve 90 and shaft 40 in a manner well understood.

Likewise the steam imparts to the cut-off sleeve 20 and its shaft 25 a tendency to move endwise to the left. This is resisted by the engagement of the projecting left end of 25 the shaft 25 with a hardened wear plate 101 which is fixed to the fly wheel 100, which said fly wheel is likewise fixed to the shaft 40.

This fly wheel 100 is keyed or otherwise fixed to a shaft 47 which is mounted in a 30 suitable bearing 48. The projecting left end of the shaft 25 has a pinion 27 fixed to it. This is engaged by a gear segment 102 which is fixed to a rock shaft 103, the latter rock shaft being mounted on the fly wheel with its 35 axis parallel with the axis of the shaft 25. A weighted lever arm 104 is likewise fixed to this rock shaft. A spring 105 is connected at one end with the fly wheel, and at the other end with a part of the lever 104 in such 40 wise that it opposes swinging movement of the lever 104, which would otherwise result from the centrifugal force generated from the revolution of the fly wheel. Specifically spring 105 is connected with lever 104 by 45 means of a link 109, which is connected at one end with the spring 105, and at the other end is connected by means of a bolt 110 with an arm 107 which is a rigid part of lever 104,—the said bolt 110 going through a slot 50 108 in said arm 107.

Because of this construction the connection between the spring and the lever 104 may be adjusted toward and from the axis of the rock shaft 103, and thereby will the swinging movement of the lever 104, by the centrifugal force, be varied within desired limits.

To the extent that such arm does swing and thereby rock the rock shaft 103, will the shaft 25 be turned with reference to the 60 engine shaft 40. When it is so turned, the cut-off sleeve will likewise be turned in the direction such as will shorten the time during which steam may pass through the ports 23 into the engine cylinder. That is to say, 65 after the speed of the engine shaft reaches a

predetermined maximum, any increase in speed will result in so turning the cut-off sleeve that it will shorten the period of time during which said sleeve permits the passage of steam from it outward toward the 70 engine cylinder.

Packing rings 35^a are set into the surface of the inlet sleeve 30 at opposite ends of the ports 33, and these engage the inner periphery of the recess in the shaft 40 within which 75 said sleeve is fitted. Longitudinal packing strips 56^a are likewise set in the surface of this sleeve on opposite sides of the ports therein, and these likewise engage the shaft. Similarly, annular packing rings 28 and 80 longitudinal packing strips 29 are set into the surface of the cut-off sleeve and these engage the inner periphery of the sleeve 30.

A packing disk 46^a surrounds the shaft 25 and engages the inturned end flange of the 85 steam inlet sleeve 30, and serves, in a large degree, to prevent the passage of steam around the shaft 25.

Likewise there is a stuffing box carried by the shaft 40 adjacent to the enlarged recess in said shaft and the shaft 25 passes through it.

The lubrication of the described mechanism may be efficiently secured by the means shown in Fig. 1. That is to say, the steam 90 inlet pipe 36 has connected into it a box 64 having a removable side plate 65. A two part cage 66 contains a plurality of rings 67 which embrace the edges of the wire gauze disk 68. When this cage is put into the 100 casing 64 and the cover 65 is put on, oil is discharged into the inlet pipe through a pipe 69. This oil will be drawn along by the steam, and will be thoroughly broken up into a spray by its passage through the plurality 105 of wire gauze screens 68, and this spray carried along by the steam will reach every part of the engine requiring lubrication.

The term elliptoid applied to the chamber within the cylinder is not to be construed as 110 limited to the exact form shown,—but is to be regarded as inclusive of any symmetrical non-cylindrical chamber adapted to engage with the piston blades and to perform the described function in connection therewith.

Having described my invention, I claim:

1. In a rotary engine, the combination of a cylinder containing an elliptoid chamber, and the following parts therein arranged concentrically one within another, viz., a centrally placed cut-off sleeve, which sleeve rotates with the engine shaft and may be moved angularly with respect to the said shaft, means for turning the said sleeve, a fixed steam inlet sleeve, an engine shaft, and 120 a rotor fixed to the shaft, radially movable blades carried by said rotor, and a steam inlet pipe connected with said fixed sleeve,—the said four concentric parts having steam 125 ports through which steam may pass from 130

the cut-off sleeve into the space between the rotor and the cylinder, and means connecting the shaft and cut-off sleeve.

2. In a rotary engine, the combination of a cylinder containing an elliptoid chamber, and the following parts therein arranged concentrically one within another, viz., a centrally placed cut-off sleeve, which sleeve rotates with the engine shaft and may be moved angularly with respect to the said shaft, a fixed steam inlet sleeve, a shaft and a rotor fixed to the shaft, radially movable blades carried by said rotor, and a steam inlet pipe connected with said fixed sleeve,— the said four concentric parts having steam ports through which steam may pass from the cut-off sleeve into the space between the rotor and the cylinder, and means connecting the shaft and cut-off sleeve, said means permitting angular movement of the cut-off sleeve and shaft.

3. In a rotary engine, the combination of a cylinder containing an elliptoid chamber, and the following parts therein arranged concentrically one within another, viz., a centrally placed cut-off sleeve, which sleeve rotates with the engine shaft and may be moved angularly with respect to the said shaft, a fixed steam inlet sleeve, a shaft and a rotor fixed to the shaft, radially movable blades carried by said rotor, and a steam inlet pipe connected with said fixed sleeve,— the said four concentric parts having steam ports through which steam may pass from the cut-off sleeve into the space between the rotor and the cylinder, means connecting the shaft and cut-off sleeve, said means permitting angular movement of the cut-off sleeve and shaft, and automatic governor mechanism controlling the extent of such relative angular movement.

4. In a rotary engine the combination of a cylinder containing an elliptoid chamber and the following parts within said chamber arranged concentrically, to-wit: a centrally placed cut-off sleeve, a fixed steam inlet sleeve, a shaft, a rotor fixed shaft, radially movable blades carried by the rotor; a steam inlet pipe connected with the said fixed sleeve, the said concentric parts having steam ports through which steam may pass from the cut-off sleeve into the space between the rotor and the cylinder, means connecting the shaft and the cut-off sleeve and

means for moving the said centrally placed cut-off sleeve in its angular relation to the said shaft.

5. In a rotary engine the combination of a cylinder containing an elliptoid chamber and the following parts arranged concentrically, one within another, to-wit: a centrally placed cut-off sleeve, a fixed steam inlet sleeve, a shaft, a rotor fixed to the shaft, radially movable blades carried by said rotor, a steam inlet pipe connected with said fixed sleeve, the said four concentric parts having steam ports through which steam may pass from the cut-off sleeve into the space between the rotor and the cylinder, means connecting the shaft and the cut-off sleeve, a shaft which extends centrally through the engine shaft and is connected at the one end with the cut-off sleeve and means whereby said shaft may be operated to change the angular relationship between the engine shaft and the said cut-off sleeve.

6. In a rotary engine, the combination of a cylinder containing an elliptoid chamber, and the following parts therein arranged concentrically one within another, viz., a centrally placed cut-off sleeve, a fixed steam inlet sleeve, a shaft and a rotor fixed to the shaft, radially movable blades carried by said rotor, and a steam inlet pipe connected with said fixed sleeve,— the said four concentric parts having steam ports through which steam may pass from the cut-off sleeve into the space between the rotor and the cylinder, means connecting the shaft and cut-off sleeve, a shaft which extends axially through the engine shaft and is connected at one end with the cut-off shaft and which projects at its other end behind the engine shaft; a fly wheel fixed to the engine shaft, a pinion fixed to the cut-off sleeve shaft, a rock shaft mounted on the fly wheel having a gear segment which engages said pinion, a weighted arm fixed to said rock shaft, and a spring opposing that movement of said weighted lever arm which is produced by centrifugal force.

In testimony whereof, I hereunto affix my signature in the presence of two witnesses.

HENRY W. BOGART.
